United States Patent Office

Des. 189,356
Patented Nov. 29, 1960

189,356

STORAGE RACK OR SIMILAR ARTICLE

Leonard B. Kolkey, 11820 Navy St., Los Angeles, Calif.

Filed Sept. 18, 1959, Ser. No. 57,598

Term of patent 14 years

(Cl. D33—3)

FIG. 1.

FIG. 2.

FIG. 3.

FIG. 4.

Fig. 1 is a perspective view of a storage rack embodying the new design of my invention;

Fig. 2 is a front elevational view of this storage rack;

Fig. 3 is a top plan view of this storage rack; and

Fig. 4 is a side elevational view of this storage rack.

I claim:

The ornamental design for a storage rack or similar article, substantially as shown.
